METAL WINDOW AND STAY THEREFOR

Valentine George Crittall and Walter Cecil Bywater, Braintree, England, assignors to The Crittall Manufacturing Company, Limited, Braintree, England

Application September 11, 1935, Serial No. 40,180
In Great Britain October 12, 1934

5 Claims. (Cl. 292—262)

This invention relates to improvements in metal casement windows and more particularly to an improved construction of stay or like fitting therefor.

5 It is the present practice in metal casement windows to attach the guide bar for the swinging arm or link of the stay by securing the bar at its ends to the metal framework or the window, but this construction has certain practical disadvantages.

10 According to the invention in a metal casement window having fixed and moving frame members provided with inner and outer co-operating flanges, the guide bar for the stay arm comprises a rail provided with a retaining rib and formed in one with or united throughout its length such as by welding or riveting to one of the frame members, the other frame member supporting the stay arm which carries a clamp adapted for sliding engagement with the retaining rib of the rail.

15 In a preferred arrangement the metal section of the moving frame of the window along its lower edge is formed with an inwardly extending horizontal flange constituting the guide rail and along which flange the window clamp carried on the swinging arm is slideable.

20 The guide rail, or the metal strip forming the rail and which is attached by riveting or welding to the window section is preferably formed at its extremity with a rib of bulbous section.

25 A further feature of the invention consists in the manner of attaching the securing clamp to the stay arm by means of its tightening pin, since by anchoring the pin to the arm, it being understood that the head of the pin engages behind the arm, when the clamp is tightened the arm will be rigidly braced by the clamp to the guide rail.

30 The invention is illustrated in the accompanying drawings in which Figures 1 and 2 are respectively a part elevation and plan view of a metal casement window having a stay fitting in accordance with the invention;

35 Figure 3 is a transverse sectional view (on an enlarged scale) and showing the clamping mechanism;

40 Figure 4 is a transverse sectional elevation of an alternative construction of window section;

45 Figure 5 is a transverse sectional elevation showing a further embodiment of the invention in which the window is constructed to open inwardly.

50 Referring to the accompanying drawings there is shown a metal casement window comprising a fixed window frame A and a moving frame or

window B which is hinged to open outwardly about a centre C (see Figure 2).

5 On the window frame A is a bracket D, to which is pivoted one end of a swinging arm or link E of the stay. The other end of the swinging arm carries a clamp indicated generally at F and which is in sliding engagement with a guide bar I on window B.

The essential feature of this invention consists in a construction in which the guide bar forms 10 a single unit with the metal section of the window and in the arrangement shown in Figures 1-3 the guide bar consists of a metal strip I attached by riveting to the vertical flange of the window section. The guide bar strip comprises an overhanging rail 3 terminating in a retaining rib 4 which preferably as shown is of bulbous section. The clamp embraces the rib along which it is slideable.

15 In the construction of Figure 4 the guide bar instead of being attached throughout its length to the section B forms an integral part of the metal section B of the window and for this purpose the vertical flange indicated at 5 of the window section is provided with an overhanging 20 rail portion 3' having the rib 4. As shown it is preferable to fit the rib 4 with a liner 4' of brass or other non-rustable material and where the guide bar is attached such as by riveting to the window section as in Figures 1-3, the entire bar 25 may be formed of brass or other non-rustable material.

30 According to a further feature of the invention the window securing lamp F, which is formed in two parts 6 and 7, is anchored to the swinging arm 35 E of the stay with the result that when the clamp is tightened in addition to its functioning to fix the window by gripping the guide bar it will also clamp together the guide bar and swinging arm and thus prevent any play therebetween. The 40 clamping members 6 and 7 are each formed with a rib-embracing recess shaped to embrace partially and circumferentially the guide bar rib 4, thereby providing a large surface area for frictional engagement of the clamping members 6 45 and 7 with the rib 4.

45 It will be appreciated that by eliminating play, between the guide bar and the swinging arm, when the window is locked at any opening, the bar and arms will be rigid with one another. This 50 is an important advantage especially when the window is set at a small window opening, since in the normal construction there is a tendency of its shutting of its own accord, due to play at the pivotal points at each end of the arm, whereas 55

with the clamp of this invention, play can only occur at the pivot between the swinging arm and the window frame.

For this purpose the two parts 6 and 7 of the clamp are secured to each other by a screw-threaded stud 8, the head or one end 9 of which is anchored to the stay arm E, its other end projecting above the parts of the clamp to receive a thumb or wing nut 10. The two parts of the clamp are grooved to correspond with the cross section of the rib 4 of the guide bar and in addition are respectively provided with a locating rib and groove indicated at 11. The thumb nut may be secured on the stud 8 by means of a screwed pin 15 12.

Referring now to Figure 5 there is shown a further embodiment of the invention as applied to an inwardly opening window, in which the metal strip 1 of the guide bar rail is secured by welding to the vertical flange of the window section B and is formed with a laterally projecting rib 13 as distinct to the arrangement of Figures 3 and 4, where the rail 3, 3' of the guide bar is inclined to the horizontal thereby providing in combination with the window pane, a condensation channel. In Figures 3 and 4 the rib 4 is on one side of the central plane of the rail but alternatively it may be central (not shown). When, however, the overhanging portion is horizontal or 25 substantially horizontal as in Figure 5, by constructing the rib to project upwardly above the plane of the metal the rib itself may be used to provide this channel.

In Figure 5 provision is made for setting the angle of the throw of the tightening piece of the clamp 10 as bounded by its locked and release positions so that it can be properly accommodated within the limited space allowed by the window glazing. For this purpose the stud 8 is 35 formed with a squared portion or spline portion 14 adapted to engage in a spline-receiving groove 15 in the lower half of the clamp, the head of the stud of course being a loose fit in the swinging stay arm E. If on assembly it is found that the thumb piece fouls the window pane, it is possible by disengaging the squared portion of the stud from the groove in the clamp and turning the screw through 90° or 180° as may be required and then re-engaging the squared portion with the groove, to adjust the setting of the throw of 50 the thumb nut.

In order to limit the travel of the clamp along the guide bar a stop formed by means of a screw 16 or by crimping a portion 17 of the bar itself may be provided.

The sliding stay construction of this invention possesses several advantages chief among which is its neatness of appearance while when the window is in its closed position the swinging stay arm tucks beneath the flange forming the guide bar. Moreover by constructing one of the operating members of the stay as a part integral with the framework of the window, the number of loose parts is reduced.

Moreover, as compared with the existing practice of attaching the guide bar to the window section at its ends, the present arrangement has the further advantage that the range of travel of

the clamp is increased since it is permitted to move the entire length of the flange.

While the invention is mainly intended for side hung windows with reference to which it has been particularly described, it will be understood that it is applicable to other forms, i. e., top hung, bottom hung, and pivoted.

Although not illustrated it will be obvious that if desired the guide bar or portion of the stay may be integral with the fixed frame or section 10 of the window, although such an arrangement is not so practical as one of the advantages of attaching the guide bar to the moving frame is that it can be utilized as a condensation channel.

What we claim is:—

1. In a casement window of the class wherein a frame part is movably supported with respect to a fixed frame part, and in which the moving frame part is provided with a guide rail and the fixed frame part has attached thereto a stay arm, 20 the combination with said guide rail and said stay arm of a clamp including a two-part sliding member adapted frictionally to engage said guide rail, and a clamping pin extending through the stay arm and the two parts of the sliding member and being positioned to exert clamping pressure on both the two-part sliding member and the stay arm whereby the clamp, the guide rail, and the stay arm will be rigidly locked together.

2. Combination as defined in claim 1 and in 30 which the guide rail is united throughout its length to the movable frame part.

3. The combination as defined in claim 1 and in which the guide rail comprises a rib of bulbous section for engagement by the clamp and in 35 which the clamping parts are shaped to embrace said rib of bulbous section.

4. In a casement window of the class wherein a frame part is movably supported with respect to a relatively fixed frame part, the combination 40 of a guide bar fast with one of said frame parts and comprising an over-hanging rail portion terminating in a relatively heavy rib of bulbous or substantially circular cross section extending in spaced relation to the frame part which carries said guide bar; a stay arm attached to the other frame part; and a clamp for rigidly but releasably securing said stay arm to said guide rail at selected points therealong and including two clamping members each formed with a rib-embracing recess shaped to embrace partially and circumferentially said guide bar rib, a clamping pin passing through the stay arm and both of said clamping members and a clamping nut positioned to cooperate with said pin for exerting 55 clamping pressure on both clamping members and the stay arm.

5. In a casement window of the class referred to in claim 1, the combination as defined in claim 1 and in which the securing clamp includes two 60 pieces mounted for sliding engagement with the guide rail, one of said pieces being formed with a spline-receiving portion and an adjusting pin provided with a spline portion cooperating with said spline-receiving portion formed on one of 65 the clamp pieces.

VALENTINE GEORGE CRITTALL,
WALTER CECIL BYWATER.
